PARAFFIN REMOVER FOR OIL WELLS

Karl C. Ten Brink, Wichita Falls, Tex.

Application October 20, 1936, Serial No. 106,699

3 Claims. (CL 166—17)

This invention relates to the class of wells and pertains particularly to oil wells.

In the operation of oil wells in certain sections, considerable difficulty is experienced from the accumulation of paraffin in the well tubing which acts as an obstacle to the passage of oil through the tubing and requires the cessation of operations at frequent intervals for its removal. At the present time the practice is to withdraw the sucker rod so that chemicals or other substances which will melt the paraffin can be introduced into the tubing to effect its release from the wall thereof. This results in the passage of the paraffin down to the bottom of the well, where it mixes with the oil and spreads through the oil bearing strata and is then likely to interfere with the proper flow of the oil. Considerable damage is often done to the pumping mechanism carried by the sucker rod in withdrawing it from the tubing.

The present invention has for its primary object to provide an improved means of releasing the paraffin in the tubing and effecting its discharge through the top of the tubing without allowing any of the paraffin to get into the bottom of the well.

Another object of the invention is to provide a novel means of releasing the paraffin from the interior of the well tubing by the application of steam or gases to the paraffin in the tubing above the pumping mechanism and the removal of the melted paraffin either by pressure introduced into the tubing or by the regular pumping mechanism which is employed for forcing the oil upwardly in the tubing.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view illustrating in section a portion of a well casing with the derrick floor and showing the mechanism embodying the present invention in elevation in association with the well tubing.

Fig. 2 is an enlarged sectional view of the paraffin releasing structure embodying the present invention.

Fig. 3 is a sectional view on the line 3—3 of Fig. 2.

Referring now more particularly to the drawing, the numeral 1 designates a conventionally illustrated portion of the derrick floor of an oil well structure, while the tubing which is usually introduced into the ground and through which the pumping mechanism is lowered, is shown in longitudinal section and indicated by the numeral 2.

In carrying out the present invention, the well tubing, which is here generally designated by the numeral 3, is divided into the upper and lower portions 4 and 5 between which is coupled a relatively long cylinder which is indicated generally by the numeral 6. This cylinder consists of the two cylindrical portions 7 and 8, each of which at one end terminates in a constricted part 9 and an interiorly threaded collar 10 into which an end of an adjacent portion of the well tubing is threaded secured, as illustrated. The abutting ends of the portions 7 and 8 are coupled together by a collar 11. The constricted end of the upper portion 7 of the cylinder is provided with the upwardly directed boss 12 through which a threaded aperture 13 is formed. In the inner end of this threaded aperture there is secured one end of a pipe section 14 which extends downwardly into the cylinder to approximately the center thereof, as illustrated in Fig. 2, while the outer end of the passage opening 13 has a pipe line 15 coupled therewith which leads upwardly through the derrick floor 1, as illustrated. This line may be provided with a valve 16 which is accessible to an operator upon the derrick floor and it also has interposed therein a check valve 17 which is shown in detail in Fig. 3 and which is intended to open downwardly so that back pressures created in the cylinder 6 will be shut off from passage into the pipe line 15.

The upper end of the well tubing is turned to extend laterally as is the usual practice, so that fluids pumped upwardly through the tubing can be carried off without interfering with the operation of the sucker rod which is indicated generally by the numeral 18, and which passes downwardly through the cylinder 6 to the mechanism at the lower end of the well tubing which is not illustrated.

The formation of paraffin in an oil well occurs at a depth of approximately twelve hundred feet and at points above this level, therefore the cylinder 6 will be located at approximately the twelve hundred foot level in the oil well. In the operation of the device, when it is necessary to re-

move paraffin from the well tubing, the pipe line 15 will be connected with a suitable source of gas under pressure or with a steam generator so that the gas or steam may be introduced through the pipe into the cylinder 6. Here and above this depth the paraffin in the tubing will be melted, and additional pressure either of steam or gas, may be employed for discharging the melted paraffin from the top of the tubing. Due to the 10 pumping mechanism in the lower end of the tubing, moisture resulting from condensation of the steam and also the melted paraffin will be prevented from flowing downwardly and escaping into the well. It will also be obvious that the melted paraffin may also be removed by operating the sucker rod so that it will be pumped out with the oil.

From the foregoing it will be readily apparent that with the present device it will not be necessary to withdraw the sucker rod from the well tubing when it is necessary to remove paraffin therefrom, and therefore the usual damage to the pumping mechanism which accompanies this 20 operation, will be avoided, and it will also be apparent that the damage which would be done to the well by the escape of melted paraffin and steam into the lower portion thereof if the sucker rod were removed, will be avoided, as the pumping mechanism shuts off the tubing as previously 25 explained, and prevents the paraffin and condensed steam from escaping into the well.

What is claimed, is:

1. In an oil well including a tubing and a sucker rod extending therethrough, a cylinder coupled 30 in the line of tubing, the sucker rod extending through the cylinder to the mechanism in the lower end of the tubing, and a valved pipe line leading into said cylinder whereby a fluid may be

introduced thereinto to flow upwardly through the tubing, said valve opening only toward the cylinder.

2. In a mechanism of the character described, oil well tubing, a cylinder having opposite ends provided with threaded openings, said tubing being divided and having its adjacent ends connected and terminating in the threaded openings of the cylinder whereby the cylinder forms throughout its length an oil passageway between said ends, a threaded passage formed through the wall of the cylinder, a pipe line having an end extended through and secured in said threaded passage, and a check valve in said pipe line which opens toward the cylinder whereby fluid under 10 pressure may be introduced into the cylinder from said line to return through the tubing.

3. In an oil well construction, an elongated cylinder having each end constricted and terminating in an interiorly threaded collar, a well tubing 20 divided into upper and lower portions and having the adjacent ends of the portions threaded and each engaged in and terminating at a threaded collar whereby the cylinder is coupled in and forms a part of the tubing, a sucker rod passing through the tubing and cylinder and carrying in the tubing below the cylinder the usual pumping mechanism whereby the tubing is closed against the down flow of fluids therethrough, a pipe line 25 paralleling the upper portion of the tubing and entering said cylinder, and a check valve controlling said pipe line and opening downwardly toward the cylinder whereby fluid under pressure may be introduced into the cylinder to effect the 30 discharge of softened paraffin upwardly through the tubing.
